UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

GAS STOVE.

Application filed December 26, 1917. Serial No. 208,745.

To all whom it may concern:

Be it known that I, HENRY W. O'Dowd, a citizen of the United States, and a resident of Jersey City, county of Hudson and State 5 of New Jersey, have made certain new and useful Improvements in Gas Stoves, of which the following is a specification.

The invention relates to gas stoves, and more particularly to means for controlling 10 the supply of gas to the burners of a gas stove and for indicating the operation of said means.

Objects of the invention are to provide an improved form of gas stove which shall be 15 proof against leakage of gas; whose gas supply means may be operated with safety, certainty and convenience; which shall be capable of indicating the operation of said gas supply means; and which shall be simple and durable in construction and economical, efficient and certain in operation. These and other objects of the invention will 20 in part be obvious and in part be more fully explained in the following description.

25 The invention consists in the novel parts, improvements, combinations and features of construction herein shown and described.

In the accompanying drawings, which are referred to herein and form part hereof, is 30 illustrated an embodiment of the invention, the same serving in connection with the description herein to explain the principles of the invention.

Of the drawings:

35 Fig. 1 is a front elevation of a gas stove constructed in accordance with the invention;

Fig. 2 is a view, partly in longitudinal central section, taken on the line 2—2 of 40 Fig. 4, and partly in perspective, showing a valve forming a feature of the invention and its connection to the main gas supply pipe;

Fig. 3 is a front view, partly in section 45 and partly in perspective, illustrating means for limiting the movement of the rotating member of the valve;

Fig. 4 is a perspective view of means for operating the valve;

50 Fig. 5 is a front elevation of the dial and pointer which indicate the position of the valve; and

Fig. 6 is a section taken on the line 6—6 of Fig. 5.

55 A gas stove constructed in accordance

with one feature of the invention includes, in combination, a main gas supply pipe, a plurality of branch gas supply pipes, and means for controlling the supply of gas to said branch pipes, whereby gas will be supplied to one only of said branch pipes at a time.

In one embodiment of this feature of the invention, the main gas supply pipe has a pair of branch supply pipes communicating therewith, and a valve is arranged between said main and branch pipes, said valve having ports arranged to communicate between said main pipe and one only of said branch pipes at a time.

According to another feature of the invention, means are provided for operating the valve and for indicating its position with relation to the supply pipes, whether closed or open, and if open, to which branch pipe the gas is being supplied. In one embodiment of this feature of the invention, a dial is provided which has marked thereon the various positions of the valve with relation to the branch supply pipes and the burners fed thereby, and a pointer for indicating said positions is provided, there being also provided connecting means, as a rod, between the pointer and the valve, the connection of said rod with the pointer and valve being so arranged that by moving the pointer to any desired position on the dial, the rod will be caused to actuate the valve to move to the position so indicated.

These and other features of the invention 90 will be more fully set forth in the following description and in the drawings.

Referring now in detail to the drawings, there is illustrated therein as a preferred embodiment of the invention, a gas stove 95 which has the usual top 7, to the burners of which gas is supplied by a main gas supply pipe 8 and connecting pipes, the supply of gas through which is controlled by the valves 9 and 11. There are also provided 100 a broiler 12, suitably arranged in the compartment 13, and having the usual Bunsen tube 14 and an oven 16 heated by a burner 17 conveniently arranged in said oven and having the usual Bunsen tube 18.

105 Gas is supplied to the broiler burner 12 and oven burner 17 through the main gas supply pipe 8 which communicates with the branch supply pipes 21 and 22, which in turn communicate, respectively, with the 110

broiler burner 12 and the oven burner 17. In gas stoves of this type in which the supply of gas to the burners of the broiler and the oven, respectively, is controlled by independent means or valves, there is the liability to leakage of gas with its consequent evils because of the opportunity afforded the user to omit for any reason to close the valve of one burner before opening that of the other.

A feature of the invention, therefore, resides in the means provided whereby the gas provided for the broiler burner 12 and the oven burner 17 can be supplied to one only of said burners at one time. Preferably and as shown, said means comprise a valve 23 which is arranged to communicate with the main gas supply pipe 8 and also with the branch gas supply pipes 21 and 22. Said valve 23 comprises an outer casing 24 and an inner rotating member 25 which is formed with a diametral port 26, which port, in the position of the parts shown in Fig. 2, at one end 27 communicates with the branch pipe 21 leading to the broiler burner 12, and at its other end 28 communicates with the branch supply pipe 22 leading to the oven burner 17. The valve inner member 25 is formed also with another port 29 at right angles to the port 26 and adapted, when in certain positions to which further reference will be made, to communicate with a port 30 formed in the outer casing 24 of the valve and through this latter port 30 to communicate with the main supply pipe 8.

It will be noted that when the valve 23 is arranged in the said position shown in Fig. 2, its diametral port 26 will be in open position toward or communicating with both the branch pipes 21 and 22, but the port 29 will be in closed position, that is, not communicating with any of the pipes 8, 21 or 22, and hence the gas will not be supplied to either said broiler burner 12 or said oven burner 17. This may be termed the normal closed position of the valve. In order to supply gas to the broiler burner 12, for instance, the valve member 25 should be rotated through a quarter revolution in the direction to bring the end 27 of the diametral port 26 into communication with the port 30 and the supply pipe 8 and to bring the port 29 into communication with the branch supply pipe 21, while the port 26 will be closed at its end 28 by the inner wall of the outer casing 24. Conversely, if it is desired to supply gas to the oven burner 17, the valve member 25 should be turned in the direction opposite to that just described and in the direction to bring the end 28 of the port 26 into communication with the port 30 and the pipe 8, and to bring the port 29 into communication with the branch supply pipe 22 leading to the oven burner 17.

It will be noted further that if, for exam-

ple, the rotation of the valve member 25 from its closed position to its open position with relation to the broiler, as described, could be continued further through, say, another quarter revolution, the port 29 then 70 would be in communication with the port 30 and pipe 8, and the diametral port 26 would be in communication with the pipes 21 and 22, this arrangement of the valve and the supply pipes permitting the supply of 75 gas to the broiler and oven simultaneously. In like manner, a similar continuation of the rotation of the valve member 25 from its closed position to open position with relation to the oven supply pipe, as described, 80 would bring about communication between the port 29 and the port 30 and pipe 8 and between the diametral port 26 and the said supply pipes 21 and 22, and thus permit the supply of gas to both broiler and oven 85 at one time.

Means are provided, therefore, for limiting the movement of the rotating member 25 of the valve 23 and preventing the possibility of the effecting of any arrangement of 90 the valve 23 and the supply pipes 8, 21 and 22, which would permit communication between the said pipe 8 and the said pipes 21 and 22 simultaneously, as described. Preferably and as shown, see Fig. 3, the outer 95 casing 24 of the valve 23 is constructed with a portion 31 projecting at one side somewhat beyond the other portion 32 on the other side, and forming on opposite edges stops 34 and 36 with each of which a pin 37 rigidly attached to the exposed portion 38 of the inner valve member 25 contacts, when the said inner member 25 is rotated in a proper direction a quarter revolution from its normal closed position, as shown in Fig. 100 2. It will be seen that the construction and relative arrangement of the valve parts and ports, the pin 34 and the pipes 8, 21 and 22, are such that when the inner valve member 25 is rotated through the said quarter revolution in either direction from its normal 105 closed position, the ports and pipe which should then be in communication, as above explained, will be in exact registry for full and proper communication.

Additional means for limiting the movement of the valve member 25 to a half revolution or quarter revolution in either direction from its normal closed position are provided in connection with another feature 110 of the invention, the indicator, which will presently be described.

It will be observed, furthermore, that in the construction described, the valve member 25 can be turned from its open position 115 with relation to the broiler supply pipe 21 to the open position with relation to the oven supply pipe 22, or vice versa, only by passing through the closed zone, that is to say, only by turning the valve member 25 first 120

to closed position and then to the open position desired. This not only prevents the supply of gas to the broiler and oven simultaneously but affords the further advantage that leakage of gas is avoided while passing from one open position of the valve to another.

Means are provided for operating the valve, which means comprise, as shown, a wing 39, preferably rigidly attached to or forming an extension of the valve member 25 and by means of which, as will be apparent, said valve member will be actuated. As the gas supply pipes and the valve 10 23 may not in all cases be easy of access, means are also provided, see Fig. 4, by which the valve may be operated from a more convenient position, say, in front of the stove. Said means comprise a bar 41 15 of suitable length to reach from the valve 23 to the front of the stove. While the bar 41 may be fastened to the valve 23 in any suitable manner, it is desirable, for reasons pertaining to the indicating feature of the 20 invention presently to be described, that the bar 41 be yieldingly connected to the valve, and, therefore, preferably and as shown, the inner end of the bar is bifurcated or forked 25 to engage, between the resulting tines 42, the wing 39. Through orifices 43 in the tines 30 42 of the bar 41 and through an orifice 44 in the wing 39 extends a pin 45 which thus serves to hold the bar and wing in secure 35 engagement. To permit the engagement to be yielding, however, the orifice 44 is made somewhat larger than the respective orifices 43, which permits a reciprocatory movement of the bar 41 in the direction of its length, the purpose of which will presently be explained. The pin may be of any desired 40 form or construction, as shown, a cotter pin made of spring metal being employed. The bar 41 terminates in a member 46 by means of which the bar may be operated to actuate 45 the valve member 25. The member 46 also serves another purpose, to which further reference will be made.

According to another feature of the invention, means are provided for always indicating the position of the valve, whether in its normal closed position or in open position with relation to the broiler or the oven. In the embodiment of the invention illustrated in the drawings, a dial 47 is suitably 50 fastened to the casing of the stove at a convenient point, said dial having formed therethrough an orifice 48 through which extends the outer end of the bar 41 to which is attached the member or pointer 46. It will be 55 seen that by turning the pointer 46 in the proper direction, the bar 41 will also be similarly turned and with it the rotating member 25 of the valve 23. At the proper places on the dial, see Fig. 5, will be marked the 60 65 points to which the pointer 46 must be

turned in order to put the valve in the corresponding respective positions. By turning the pointer 46 to the point marked "Broiler", for example, the valve member 25 will be turned to its open position with relation to the broiler burner, and thus gas will be supplied to said burner. Similarly, if the pointer 46 be turned to the point marked "Oven", the valve member 25 will be turned to the position proper for supplying gas to the oven burner. In like manner, if the pointer 46 be placed at the point marked "Gas off", the valve member 25 will be positioned in its normal closed position, that is, cutting off the supply of gas to the stove. As heretofore explained, the rotating valve member 25 can only be turned from its open position with relation to the broiler burner to its open position with relation to the oven burner, or vice versa, by turning said member 25 in the direction in which the valve should be arranged in order to cut off the supply of gas. Thus, to move the pointer 46 and so actuate the valve member 25 from broiler to oven or the reverse, the pointer 90 must be moved in the direction to pass the point marked "Gas off."

As has heretofore been alluded to, additional means are provided in connection with the indicating means for limiting the movement of the valve, said additional means, preferably and as shown, consisting of bosses 49 and 51 formed and suitably disposed on the face of the dial 47, see Fig. 5, so that the pointer 46 will, preferably through its shoulder 52, presently to be described, contact with the appropriate boss when the pointer 46 has reached the open position with relation to the broiler or oven burner, and further movement in that direction will 105 thus be prevented.

Means are provided for locking the pointer 46 and the rotating member 25 of the valve 23 in any position to which they are moved and thus further safeguarding the operation 110 of the stove. In the embodiment of the invention illustrated recesses 53, 54 and 55 are formed on the dial 47 in the vicinity of and communicating with the orifice 48, and the shoulder 52 is formed at the base of 115 the pointer 46 and is adapted to fit snugly between the side walls of the respective recesses 53, 54 and 55. The said shoulder 52 is preferably so located that, when the pointer 46 is in position indicating "Gas off", 120 the shoulder may be placed in the recess 54. As shown, the other recesses 53 and 55 are located each at a distance from the recess 54 equal to a quarter revolution of the pointer 46, so that when the pointer indicates the position "oven", the shoulder 52 will rest in the recess 55, and when the pointer indicates the position "broiler" the shoulder 52 will be positioned in the recess 53. It will be seen that when the shoulder 125 130

52 is thus placed in one of the recesses 53, 54 or 55, the pointer is secured against further rotation in any direction. In order, however, to hold the shoulder 52 in the 5 recess in which it may be placed and thus prevent accidental movement of the pointer 46 and the valve member 25, means are provided for locking the said shoulder 52 in the said recess. In the preferred embodiment of the invention illustrated in the drawings said locking means comprise a spring member 57, made of suitable metal, which is fastened in any desired way to the reverse side of the dial 47. This spring member 15 is bifurcated at its lower portion loosely to engage the bar 41 upon which is formed a stop member 58 against which the lower end of the spring 57 abuts, all as clearly shown in Fig. 4. It will be observed that 20 any withdrawal movement of the shoulder 52 from any of the recesses 53, 54 or 55 in which it may be placed preparatory to moving the pointer 46 must be made against the action of the spring member 57, which member 25 is made of a suitable strength to insure the secure locking of the shoulder 52 in any of the said three recesses and yet not to interfere with the proper manipulation of the pointer. To unlock the valve for operation, 30 it is merely necessary to pull outwardly on handle 46 against the tension of spring 57, whereupon the valve may be turned.

It will be seen that a gas stove constructed in accordance with the invention as hereinbefore described will carry out the objects of the invention as enumerated and will possess in addition other advantages which will be apparent to those skilled in the art.

In its broader aspects the invention is not 40 limited to the precise construction shown

and described nor to any particular construction by which the invention has been or may be carried into effect, as many changes may be made in the details thereof without departing from the main principles of the 45 invention or sacrificing its chief advantages.

I claim:

1. A valve mechanism for gas stoves or the like, comprising a casing, a rotary plug 50 therein, a rotatable and longitudinally movable actuating member slidably connected to said plug and provided at one point in its length with a projecting lug, a locking plate supported independently of the casing 55 and formed with a plurality of recesses to cooperate with said projecting lug, and a spring acting on the actuating member and normally holding its projecting lug in engagement with one of the locking recesses. 60

2. A valve mechanism for gas stoves or the like, comprising a casing, a rotary plug therein, a rotatable and longitudinally movable actuating member slidably connected at one end to said plug and provided at its 65 free end with a combined handle and pointer, a projecting lug formed on said actuating member at a point between its ends, a combined dial and locking plate supported independently of the valve casing adjacent the 70 free end of the actuating member and formed with a plurality of recesses to cooperate with its projecting lug, and a spring acting on the actuating member and normally holding the projecting lug in engagement with one of the locking recesses. 75

In testimony whereof, I have affixed my signature hereto,

HENRY W. O'DOWD.
